UNITED STATES PATENT OFFICE

HENRY SCHWARTZ, OF CHICAGO, ILLINOIS

CONTAINER

Application filed July 9, 1928. Serial No. 291,422.

My invention relates to containers in general, but more particularly to cans, or drums, for fluids such for example, and more especially, lubricating oil; and my primary object is to prevent re-sealing of the containers by the plugs furnished thereon, after the opening of the containers for the removal of their contents, but permitting of the subsequent sealing of the containers by plugs of a different size, thereby to prevent unscrupulous persons from removing the contents of the containers and substituting other contents therefor and disposing of such substituted contents in place of the original contents, and to provide simple and economical means for this purpose.

Referring to the accompanying drawings:

Figure 1 is a sectional view through the plug-equipped portion of a container embodying my invention, this view showing the positions assumed by the parts of the plug at the conclusion of the operation of screwing the plug into place in the filler opening of the container.

Figure 2 is a view like Fig. 1 of the construction therein shown, this view showing the positions assumed by the parts upon the initial rotation of the plug for removing it from the filler opening.

Figure 3 is a bottom plan view of the plug with the parts thereof positioned as shown in Fig. 1, the collector for the cuttings being removed.

Figure 4 is a bottom plan view of the plug with the parts thereof positioned as shown in Fig. 2 this view also showing the collector removed.

Figure 5 is a view in side elevation of the plug; and

Fig. 6, an enlarged broken sectional view of the bushing forming a part of the structure of Fig. 1.

In the particular illustrated embodiment of my invention, the wall in which the filler opening is provided, and which may be the top wall of the container, is represented at 6 and is shown as apertured at 7 to which portion an internally threaded flanged ring 8 is secured. The edge portion of the wall 6 surrounding the opening 7 is deflected as repre-

sented at 9, this deflection being shown as extending outwardly and affording an annular recess 10 in which the annular flange 11 of the ring 8 is seated and in which it is secured, as for example by welding.

Screwed into the internal threads 12 of the ring 8 is a bushing 13 externally and internally screw-threaded as represented at 14 and 15, respectively. In the particular arrangement shown both the internal and external threads of the bushing are right-hand threads, and the bushing is assembled with the ring 8 by screwing it upwardly into this ring, the external thread on the bushing being shown as extending short of the lower end thereof as represented at 14^a, thereby preventing the unscrewing of the bushing from the ring when force, externally of the container, is applied against this bushing by the unscrewing of the plug, hereinafter referred to, from the bushing and tending to rotate the bushing in counterclockwise direction.

The plug provided for sealing the bushing-equipped filler opening of the can, is represented at 16, it being externally screw threaded as represented at 17 at which it is adapted, when rotated in clockwise direction, to screw into the internal threads 15 of the bushing, a gasket 18 being preferably interposed between the upper, annular, flange portion 19 of the plug and the opposing end of the bushing 13 and the wall portion of the container, as shown.

In accordance with my invention means are provided for so mutilating the internal thread 15 of the bushing, upon unscrewing the plug 16 therefrom, as to prevent the re-sealing of the container by the plug removed therefrom. These means may be of any desirable form such, as for example, those shown in the drawings and which operate to cut away the internal thread 15 of the bushing upon unscrewing the plug therefrom.

According to the particular illustrated embodiment of these means, the bottom of the plug 16 contains a centrally disposed recess 20, the upper wall of which contains diametrically opposed recesses 21 which open through the side wall of the plug, as shown. Located in the recesses 20 are cutting tools

22 through which pivoting screws 23 secured in the plug, extend, the recesses 21 being so shaped that these cutting tools are adapted to have slight pivotal movement about the 5 pivots 23.

The cutting tools 22 are of such form, as shown, that in the screwing of the plug to place in the bushing 13 they occupy the position shown in Figs. 1 and 3 and do not damage 10 the thread of the bushing, but as soon as the operator starts to unscrew the plug from the bushing the friction between the thread 15 of the bushing and the opposed end-surfaces of the cutters, causes the cutters to rotate to the position shown in Figs. 2 and 4 thereby causing their cutting edges to engage the thread 15 of the bushing and cut it away in the unscrewing of the plug.

The cutting tools 22 are preferably so proportioned and arranged that the one which first engages the thread in the operation of unscrewing the plug and represented at the left-hand side of Fig. 4, only partially cuts away the thread 15 of the bushing and the 25 other cutter completes the cutting away operation.

The plug is preferably provided with means for collecting the cuttings produced by the action of the cutting tools 22 these 30 means comprising a dished plate 24 secured centrally, as by a screw 25, to a central depending lug 26 on the body of the plug.

It will be understood from the foregoing that it is not possible to remove the plug 16 35 from the bushing 13, with these parts assembled with the other parts of the container as shown, without so mutilating the internal thread of the bushing that the container cannot be resealed by the plug; the bushing 13, 40 according to the preferred illustrated embodiment of my invention, remaining in place in the ring 8 and the cutting devices on the plug cutting away the internal thread of the bushing, when force is applied to the plug 45 for unscrewing it from the bushing, as the bushing is held against unscrewing from the ring 8.

The purpose of my invention being to provide against the sealing of the container by 50 plugs of the size originally supplied with the containers, but without rendering the container unsealable, for subsequent use, the internally and externally threaded bushing is provided, the removal of which from the 55 container, in any desirable way, causes the latter to present the threaded opening 12 into which a plug of larger size may be screwed. A bushing provided as stated is difficult of removal except by the use of ma- 60 chine shop devices and thus presents the added advantage of greatly militating against the removal of the plugs from the containers and the re-sealing of the latter with any size of screw plug.

65 While I have illustrated and described a

particular embodiment of my invention, I do not wish to be understood as intending to limit it thereto as the same may be variously modified and altered without departing from the spirit of my invention.

70 What I claim as new, and desire to secure by Letters Patent, is:

1. The combination with a container having a threaded opening, of a bushing having internal and external threads and screwed into said opening, the cooperating threads of said bushing and container being such that in screwing the bushing to place the bushing moves toward the outer end of said opening and becomes jammed in said opening, and a closure plug screwed into said bushing and provided with means operating upon the unscrewing of said plug from said bushing, to so mutilate the internal threads of said bushing as to render it unadapted for receiving 80 a similar plug.

2. The combination with a container having a threaded opening, of a bushing having internal and external threads and screwed into said opening, a threaded closure plug 90 screwed into said bushing and provided with means operating, upon the unscrewing of said plug from said bushing, to so mutilate the internal threads of said bushing as to render it unadapted for receiving a similar plug, the threads in said opening and on said bushing and plug being such that in screwing the bushing to place the bushing moves toward the outer end of said opening and in unscrewing said plug from said bushing the plug exerts a force tending to rotate said bushing in a direction to unscrew it through the outer end of said opening, and means 95 resisting said force.

3. The combination with a container having a threaded opening, of a bushing having internal and external threads and screwed into said opening, and a threaded closure plug 105 screwed into said bushing and provided with means operating, upon the unscrewing of said plug from said bushing, to so mutilate the internal threads of said bushing as to render it unadapted for receiving a similar plug, the threads in said opening and on said bushing and plug being such that in screwing the bushing to place the bushing moves toward the outer end of said opening and becomes jammed in said opening and in unscrewing said plug from said bushing the plug exerts a force tending to rotate said bushing in a direction to unscrew it through the outer end of said opening, which is resisted by the bushing being jammed as above stated, in said 115 opening.

4. The combination with a container having a threaded opening, of a bushing having internal and external threads and screwed into said opening, a threaded closure plug 120 screwed into said bushing and provided with means operating, upon the unscrewing of said 125 plug from said bushing, to so mutilate the internal threads of said bushing as to render it unadapted for receiving a similar plug.

plug from said bushing, to so mutilate the internal threads of said bushing as to render it unadapted for receiving a similar plug, and means for holding said bushing against rotation out of said opening in the unscrewing of said plug.

5. The combination with a container having a threaded opening, of a bushing having internal and external threads and screwed 10 into said opening, a threaded closure-plug screwed into said bushing and provided with means operating, upon the unscrewing of said plug from said bushing, to cut away the internal threads of the bushing, and means for 15 holding said bushing against rotation out of said opening in the unscrewing of said plug.

6. The combination with a container having a threaded opening, of a bushing having internal and external threads similarly disposed 20 and screwed at one of its threads into said opening, a threaded closure plug screwed into said bushing and provided with means operating, upon the unscrewing of said plug from said bushing, to so mutilate the internal 25 threads of said bushing as to render it unadapted for receiving a similar plug, and means for holding said bushing against rotation out of said opening in the unscrewing of said plug.

30 7. The combination with a container having a threaded opening, of a bushing having internal and external right-hand threads and screwing at its external thread into said opening, a threaded closure plug screwed into said 35 bushing and provided with means operating, upon the unscrewing of said plug from said bushing, to so mutilate the internal threads of said bushing as to render them unadapted for receiving a similar plug, and means for holding 40 said bushing against rotation out of said opening in the unscrewing of said plug.

8. The combination with a container having a threaded opening, of a bushing having internal and external threads and screwed 45 into said opening, a threaded closure-plug screwed into said bushing and provided with means operating, upon the unscrewing of said plug from said bushing, to so mutilate the internal threads of said bushing as to render 50 it unadapted for receiving a similar plug, and means rendering said bushing in the assembled condition of said parts inaccessible for application of a tool thereto for rotating it in said opening.
